UNITED STATES PATENT OFFICE.

RAYMOND B. GILCHRIST, OF NEWARK, NEW JERSEY.

SQUEEZER.

980,628.

Specification of Letters Patent.

Patented Jan. 3, 1911

Application filed October 25, 1906, Serial No. 340,451. Renewed October 24, 1910. Serial No. 588,898.

To all whom it may concern:

Be it known that I, RAYMOND B. GILCHRIST, a resident of Newark, in the county of Essex and State of New Jersey, have invented certain new and useful Improvements in Squeezers, of which the following is a full, clear, and exact description.

The invention relates to devices commonly known as squeezers and more particularly to that class used for small articles such as limes.

The invention designs to provide an improved lime-squeezer which is simple in construction. In practice devices for this purpose are usually made of non-corrosive metal, *e. g.* aluminum, which is a rather soft metal. In manufacturing these devices from such metal it has been found difficult to provide a pivotal connection between the soft metal parts which does not become worn or quickly wear the soft metal parts.

One object of the invention is to provide an improved pivotal connection between the members which is specially advantageous in devices of this character, when made of soft metal parts.

Another object of the invention is to provide a device embodying members each having an integral jaw and handle and an improved strainer.

Another object of the invention is to provide an improved construction in which the spring for normally holding the jaws apart is held between the pivotally connected members, where it cannot be affected by juice expressed from the articles.

Lastly, the invention designs to provide an improved lime-squeezer.

With these objects in view, the invention consists in the several novel features herein-after described and more particularly defined by claims at the conclusion hereof.

In the drawings: Figure 1 is a perspective of a device embodying the invention. Fig. 2 is a plan of one of the squeezer-members and Fig. 3 is a section on line 3—3 of Fig. 1.

The device comprises members A and B which are formed of non-corrosive metal such as aluminum. Member A has integrally formed therewith a jaw *a* and a handle *a'*. Member B has integrally formed therewith a jaw *b* and a handle *b'*. Each of the members is provided with a perforation through which passes a tubular rivet C which pivotally connects them. The upset end *c* of the rivet fits into an annular recess or groove

c' to prevent the upset end from projecting materially beyond the outer face of the member A. The other end of the tubular rivet is flared or forced outwardly as at *c*² to engage the outer face. Member B is also indented as at *c*³ or expanded to secure the rivet against rotation in the member B. The members are held together between the ends *c* and *c*² of the tubular rivet. This rivet is usually formed of harder metal such as brass and in practice it has been found that this pivotal connection avoids in a large measure the wear of the parts about the pivot.

Each of the members is provided on its inner face with an annular groove 10 around the pivot, and a groove 11 extends outwardly from each annular recess 10. Coil spring D is placed between the members and in the recesses and the ends of the spring extend outwardly into the grooves 11 of the members respectively and there abut against the outer edge of said groove and hold the members normally apart. This construction makes it possible to use a spring which is inclosed so it cannot be affected by juice escaping from the squeezer.

A strainer E is integrally formed with member B below the compressor-jaw *b* and is extended laterally to catch the juice expressed from the article and has a rim-portion *e* at its outer edge and a rim-portion *e'* at the opposite side thereof. Jaw *a* of member A is arranged to abut against rim-portion *e'* which serves as a stop for limiting the outward movement of the jaws. The strainer is provided with holes *e*² through which the juice expressed from the article can escape. By providing a rim for the strainer the loss of the juice is avoided and one portion thereof serves as a stop for limiting the relative movement of the members.

Each jaw is provided with transversely extending ribs 14 which extend straight across the jaw and the jaws are substantially straight transversely. The purpose of the ribs is to grip the article and hold it between the jaws. The handles of the members comprise respectively a side portion 15 and a transversely extending portion 16. This construction is such that the members can be readily cast without the use of complex molds and will be strong and can be conveniently grasped in the hand.

By forming the handles so they are angular in cross section and with a transverse rib

at their outer edges they are rendered strong and rigid when made of soft metal, and furthermore, they can be very readily cleaned to prevent accumulation of objectionable matter as would be the case if pockets or channels were formed therein.

The invention possesses several important advantages. The device can be made of as soft non-corrosive metal as desired and will nonetheless be durable and strong. The improved pivotal connection is simple and adds substantially no weight to the device and prevents undue wear at the pivotal connection. One material advantage of the arrangement of the spring is that the juices of the rim do not come in contact therewith. When an exposed spring is used the juice corrodes it and this is objectionable. The construction of the strainer, transverse ribs on the jaws and handles, is such that the parts can be produced at a low cost and so the device can be made of aluminum without danger of breakage in ordinary use.

Having thus described the invention, what I claim as new and desire to secure by Letters Patent is:

1. In a squeezer, the combination of two members each having a jaw and a handle formed of soft metal, and a tubular rivet of harder metal extending through both of the members and upset to pivotally connect the members together and secured against rotation in one of the members.
2. In a squeezer, the combination of two members each having a jaw and a handle formed of soft metal, and a perforation

therein, and a tubular rivet of harder metal extending through the perforations in said members and impressed to secure the rivet against rotation in one of the members, the other of the members having an annular recess, the rivet having an upset portion in said recess.

3. In a squeezer, the combination of a pair of members pivotally connected together, each having an integral jaw and handle, the handles being angular in cross section and comprising an inwardly extending flange at its outer edge and a side extending in the direction of the plane of movement of the jaws, the inner faces of each side being exposed, a strainer integrally formed with one of the members and extended parallel to the plane of movement of the jaws, and to underlie the other member when the squeezer is open, and a rim extending around the outer edge and side of the strainer.

4. In a squeezer, the combination of two members each having an integral jaw and handle, a pivot for connecting said members, one of the members having an annular recess around the pivot on its inner face, a spring in said recess and lying between the members, transverse ribs on the jaws, a strainer integrally formed with one of the members and extended parallel to the plane of movement of the jaws, and a rim around the strainer.

RAYMOND B. GILCHRIST.
